HENRY ZAHN, OF TOLEDO, OHIO.

Letters Patent No. 84,401, dated November 24, 1868.

IMPROVED RAILWAY-RAIL.

The Schedule referred to in these Letters Patent and making part of the same.

To all whom it may concern:

Be it known that I, HENRY ZAHN, of Toledo, in the county of Lucas, and State of Ohio, have invented a new and useful Improvement in Railroad-Rails; and I do hereby declare that the following is a full, clear, and exact description thereof, which will enable others skilled in the art to make and use the same, reference being had to the accompanying drawings, forming part of this specification in which—

Figure 1 is a side view of my improved rail.

Figure 2 is a cross-section of the same through the line $x x$ of fig. 1.

Similar letters of reference indicate like parts.

The object of this invention is to provide a railroad-rail combining several advantageous qualities.

It consists in forming the rail in two parts, namely, a solid bar or rail proper, supported by a hollow base, of triangular section, and having a longitudinal opening along its upper part, into which a tongue on the rail fits, as will be more clearly set forth by reference to the drawings, in which—

A is the rail proper, having a tongue, b, and lips e e. The tongue fits within an opening in the upper part of the base, B, which is a hollow triangular rail, formed by casting the metal in that form, or bending it by suitable machinery.

The sides of the hollow base terminate in vertical shoulders, a a, between which the tongue b fits, and upon which the weight of the rail A rests.

The lips e e form, with the tongue, recesses, in which the upper edges of the parts a a rest, thus holding it securely.

The rail A and its base are affixed together by bolts, d, passing through longitudinal slots in the tongue and the parts a a, as shown. The rail and the base break joints, and thus form a continuous rail, which, however, will expand or contract without breaking.

The downward pressure of cars upon the rail A acts to bring the parts a a toward each other, and thereby pinch the tongue, as the keystone of an arch is pinched, and thus lessening the effect of percussion and vibration in direct proportion to the downward pressure on the rail.

The hollow metallic base also affords sufficient support to permit the cross-ties to be located much further apart than is usually requisite.

Having thus described my invention,

I claim as new, and desire to secure by Letters Patent—

The hollow elastic base, B, having inwardly-inclined sides, terminating in the vertical parts a a, between which the tongue b of the rail A is bolted, whereby the rail B is depressed by the weight of the passing train, causing the parts a a to pinch the tongue b, thereby lessening the effect of percussion and vibration in proportion to the downward pressure of the rail, as herein shown and described.

The above specification of my invention signed by me, this 26th of June, 1868.

HENRY ZAHN.
